(57) **CLAIM**

The ornamental design for a nasal spray device, as shown and described.

DESCRIPTION

FIG. 1 is a perspective view according to my new design;

FIG. 2 is a front view thereof;

FIG. 3 is a side view thereof;

FIG. 4 is a top view thereof; and,

FIG. 5 is a bottom view thereof.

The broken lines shown in the drawings illustrate portions of the article and form no part of the claimed design.
